UNITED STATES PATENT OFFICE.

JOHN M. FEDDERS, OF BUFFALO, NEW YORK, ASSIGNOR TO THEODORE C. FEDDERS,
OF BUFFALO, NEW YORK.

RADIATOR.

1,017,396.

Specification of Letters Patent. Patented Feb. 13, 1912.

Application filed December 8, 1911. Serial No. 664,603.

To all whom it may concern:

Be it known that I, JOHN M. FEDDERS, a citizen of the United States, residing at Buffalo, in the county of Erie and State 5 of New York, have invented new and useful Improvements in Radiators, of which the following is a specification.

This invention relates to that class of radiators which are more particularly designed for cooling the water which is circulated around the cylinders and other parts 10 of automobile gas engines for the purpose of preventing undue heating thereof.

The object of this invention is the production of a radiator of this character which can be produced at comparatively low cost, which is not liable to leak when in use, and which may be constructed of strips of sheet metal so that two adjacent strips form a 15 unit and produce a plurality of air tubes and still give the radiator as a whole the appearance of being constructed of individual air tubes.

In the accompanying drawings consisting 20 of 2 sheets: Figure 1 is a fragmentary front elevation of a radiator embodying my invention. Fig. 2 is a vertical transverse section in line 2—2, Fig. 5. Figs. 3 and 4 are horizontal sections in the correspondingly numbered lines in Fig. 1. Figs. 5 and 6 are vertical sections in the correspondingly numbered lines in Fig. 1. Fig. 7 is a fragmentary vertical section in line 7—7, Fig. 5. Figs. 8 and 9 are fragmentary perspective 25 views of the two sections constituting one of the units of the radiator core. Fig. 10 is a similar view of the plaited section of a radiator unit viewed from the side opposite to that shown in Fig. 9.

Similar characters of reference indicate 30 corresponding parts throughout the several views.

In its general organization my improved radiator comprises an upper inlet header or 35 water box 1 to which the water is conducted in any suitable way from the part which is to be cooled, a lower outlet header or water box 2 from which the water is adapted to be conducted in any suitable manner to 40 the part to be cooled, 3 a side piece or wall connecting one of the ends of the upper header with the corresponding end of the lower header and 4 the core arranged between the upper and lower header and con-

structed to form a plurality of vertical sinuous water passages 5 which open at their upper and lower ends into the lower part of the upper header and into the upper part of the lower header, respectively, and a plurality of horizontal air tubes 6 extending 55 fore and aft of the radiator.

The headers of the radiator may be of any suitable and well known construction but the core embodies my improvements and is constructed as follows: As a whole the 60 core comprises a plurality of units each of the units being arranged vertically and the several units being arranged horizontally side by side so as to form a plurality of vertical sinuous or tortuous water passages 65 between adjacent units and a vertical row or tier of horizontal air tubes within each unit.

Each of the core units is constructed of two sections of sheet metal, preferably copper. One of these sections is formed of a 70 strip of such metal, so as to produce a plurality of flat upright webs 7 which are arranged one above the other and vertically in line, outwardly off set spacing beads 8 arranged vertically adjacent to the front 75 and rear edges of the flat webs, a plurality of horizontal longitudinal locking beads 9 each of which is arranged between two adjacent flat webs 7 and has its convex side arranged on the outer side of the respective 80 strip of metal, and a plurality of alining beads 10 each of which is arranged on the outer or convex side of one of the spacing beads in line with the adjacent locking bead and has its convex side on the outer side of the 85 respective strip of metal. The other section of each core unit is also constructed from a strip of such metal so as to produce a plurality of horizontal longitudinal plait 90 11 which are arranged one above the other 95 in a vertical tier, the inner parts or ends of the plies of each plait forming the crown thereof being connected with each other, and the outer edges of the opposing plies of two adjacent plait being connected by an upright web which is constructed to form flat 100 vertical portions 12 arranged at opposite ends of this web and at right angles to the plait, a flat upright stiffening part 13 arranged at the center of this web, two main 105 curved web portions 14 arranged on opposite sides of the flat central part 13 and having their convex sides facing outwardly,

and two shallow seats or recesses 15 formed between the outer edges of the two plies of the plait so as to face outwardly with its concave side and each seat being arranged 5 between the adjacent vertical flat end portions 12 of two webs of the plaited section and the curved intermediate portions 14 thereof.

In assembling the two sections of each 10 core unit the same are arranged vertically side by side and the inner edges or crowns of the plait 20 of the plaited section are engaged with the concave sides of the longitudinal locking beads 9 of the beaded section, thereby producing a plurality of horizontal longitudinal air passages between the 15 two sections of the unit. After the two sections of a unit have been thus assembled a line or streak of solder is applied to the 20 joints between the uppermost and the lowermost plait and their companion locking beads, for the purpose of sealing the unit against leakage of water at these places and also to prevent longitudinal horizontal 25 displacement of the unit sections relatively to each other while assembling the radiator and also while the same is in use. In assembling a plurality of such units the alining beads of the beaded section of each 30 unit engage with the alining seats 15 of the plaited section of an adjacent unit, as shown in Figs. 2, 4, 5 and 7, thereby holding the sections of adjacent units against longitudinal horizontal displacement relatively to each other both while assembling the parts 35 of the radiator and also while the same is in use.

When the several units of the core are thus assembled the upper and lower ends of 40 the core are secured in the opening in the underside of the upper header and in the opening in the upper side of the lower header by soldering the front and rear walls of these headers to the front and rear 45 sides of the core. The front and rear walls of the upper header extend downwardly along the core at least to the first plait of the several units and the front and rear walls of the lower header extend upwardly at least to the lowermost plait of the units for the purpose of producing a watertight joint between the headers and the water passages of the core. Upon assembling the several units of the core in 55 this manner an outwardly diverging space is formed between the outer ends of the plies of each plait and the adjacent curved portions 14 of the webs of the plaited unit section which space intervenes between the respective plait and the convex side of the locking bead 9 of the adjacent unit, thereby forming a tortuous water passage between adjacent units which opens at its upper and lower ends into the upper and lower water 60 headers, as shown in Fig. 2. The water

passes from the upper header down through the several tortuous passages between the several units and into the lower header and while the water is passing in this manner the same is cooled by the air passing through 70 the plurality of air passages between the core units.

The vertical grooves or channels 16 formed at the front and rear sides of the radiator between the vertical flat end portions of the webs of adjacent core units, as shown in Fig. 1, is filled with solder or a similar material, as shown at 17 in Figs. 3 and 5, thereby sealing the front and rear ends of the water passages between the several units so as to prevent leakage and also producing the appearance of comparatively heavy division lines between the several core units.

A radiator constructed in the manner just described can be produced expeditiously and economically, it furnishes the maximum cooling capacity for a given amount of metal used in its construction, and the same is remarkably strong and not liable to give 85 way and leak under the severe strains to which the same is subjected while in use.

I claim as my invention:

1. A radiator comprising inlet and outlet headers, and a core arranged between said headers and consisting of a plurality of units, each unit comprising two sections one of which is constructed of a strip of sheet metal to form a plurality of flat webs and a plurality of transverse locking beads arranged at intervals on said strip and the other section being constructed of a strip of sheet metal to form a plurality of transverse plait each of which engages at its crown with the concave side of one of the beads in the other section and a plurality of curved webs each of which connects the opposing plies of two adjacent plait and is arranged with its convex side opposite a flat web of the other section.

2. A radiator comprising inlet and outlet headers, and a core arranged between said headers and consisting of a plurality of units, each unit comprising two sections one of which is constructed of a strip of sheet metal to form a plurality of flat webs and a plurality of transverse locking beads arranged at intervals on said strip and the other section being constructed of a strip of sheet metal to form a plurality of transverse plait each of which engages at its crown with the concave side of one of the beads in the other section and a plurality of curved webs each of which connects the opposing plies of two adjacent plait and is arranged with its convex side opposite a flat web of the other section, each of said flat webs being provided adjacent to its ends with longitudinal spacing beads and each of said curved webs having its ends arranged at right angles.

gles to the plaits and engaging with the convex sides of said spacing beads.

3. A radiator comprising inlet and outlet headers, and a core arranged between said headers and consisting of a plurality of units, each unit comprising two sections one of which is constructed of a strip of sheet metal to form a plurality of flat webs and a plurality of transverse locking beads arranged at intervals on said strip and the other section being constructed of a strip of sheet metal to form a plurality of transverse plaits each of which engages at its crown with the concave side of one of the beads in the other section and a plurality of curved webs each of which connects the opposing plies of two adjacent plaits and is arranged with its convex side opposite a flat web of the other section, each of said flat webs being provided adjacent to its ends with longitudinal spacing beads and each of said curved webs having its ends arranged at right angles to the plaits and engaging with the convex sides of said spacing beads and each of said spacing beads being provided on its convex side with an alining bead which is arranged in line with one of the locking beads and said curved webs being

provided adjacent to their ends with concave seats which receive said alining beads.

4. A radiator comprising inlet and outlet headers, and a core arranged between said headers and consisting of a plurality of units, each unit comprising two sections one of which is constructed of a strip of sheet metal to form a plurality of flat webs and a plurality of transverse locking beads arranged at intervals on said strip and the other section being constructed of a strip of sheet metal to form a plurality of transverse plaits each of which engages at its crown with the concave side of one of the beads in the other section and a plurality of curved webs each of which connects the opposing plies of two adjacent plaits and is arranged with its convex side opposite a flat web of the other section and each of said plaited sections being provided between its ends with a flattened upright stiffening portion.

Witness my hand this 6th day of December, 1911.

JOHN M. FEEDERS.
